UNITED STATES PATENT OFFICE

2,427,898

VIBRATOR

Frederick Arthur Burrows, Wilmette, Ill., assignor
to Oak Mfg. Co., Chicago, Ill., a corporation of
Illinois

Application November 19, 1945, Serial No. 629,556

2 Claims. (Cl. 172—126)

1

This invention relates to a vibrator and particularly to a high frequency vibrator for use in interrupting currents. As is well known, automobile and farm radios relying upon batteries as a primary source of power utilize vibrators for interrupting direct current and stepping up such interrupted currents in a transformer. The resulting stepped-up voltages are then used in a conventional manner for supplying the plate circuits of vacuum tubes.

While conventional vibrators operated at around 100 to 110 cycles are highly satisfactory, there has long existed a demand for vibrators capable of operating at substantially higher frequencies. As is well known, the higher the frequency of interruption, the smaller becomes the physical size of transformer and filter components. While attempts have been made to provide vibrators operating at high frequencies, such attempts have generally been unsuccessful. In the main, such attempts have consisted in utilizing conventional vibrating structures and merely increasing the stiffness to thereby increase the resonant frequency of the vibrating system. The resulting high frequency vibrator has invariably had contact trouble and spring breakage.

In accordance with the invention, there is provided a structure which is mechanically different than a conventional vibrator and provides satisfactory operation at frequencies between 200 and 300 cycles per second. In general, a structure embodying the invention utilizes a solenoid instead of an electromagnet for generating the magnetic force necessary to attract an armature. An armature cooperates with the solenoid, and the relationship between the two is such that the solenoid goes through the position at which it normally would rest upon solenoid energization. In distinction to present vibrators where the armature sweeps past a pole face, the driving circuit may be maintained energized up to the dead center position of the armature. In the conventional type of vibrator, the driving circuit energization period is more critical with respect to the armature rest position. In general, it is preferred to mount the armature at opposite ends thereof on springs and utilize the armature movement for driving contacts. As will be apparent later, various modifications of the invention are possible, some of these modifications being shown in the drawing.

Thus, referring to the drawings, Figure 1 shows a structure embodying one form of the invention, the structure being shown in elevation with the solenoid and stack being shown in section. Fig-

2

ure 2 is an end view of the structure shown in Figure 1. Figure 3 is an elevation, partly in section, of a modified form of vibrator. Figure 4 is an end view of the structure shown in Figure 3 as seen from the power contact side. Figure 5 is a detail end view of the driving contacts and spring structure. Figure 6 is an elevation, partly in section, of a push-pull form of vibrator.

Referring now to Figures 1 and 2, the structure 10 comprises frame members 10 and 11 of steel, brass or any other metal or material. Members 10 and 11 have one end joined by cylinder 12 over which coil 13 is wound. Cylinder 12 preferably is of magnetic material and has smooth bore 14 within the same in which armature 15 is adapted to operate. Armature 15 may consist simply of a ferromagnetic machined cylinder so proportioned as to be freely movable within bore 14. Armature 15 is substantially shorter than the length of coil 13, the proportion as shown being somewhat greater than one-half. However, the proportion of cylinder length to coil length may vary within wide limits and will depend upon various factors such as armature travel, frequency of operation, ratio of coil diameter to coil length, flux density within armature 15 and the like.

Armature 15 is supported eccentrically of coil 12 by means of shaft 17. This may be of aluminum or brass and may pass through the center 30 of armature 15 or may be secured thereto in any desired fashion. While shaft 17 is preferably non-magnetic, its small diameter makes it unimportant whether it is magnetic or non-magnetic. Shaft 17 has threaded ends 18 and 19.

Frame members 10 and 11 at the other ends carry outwardly extending stacks 20 and 21. Between the ends of members 10 and 11 is block 22 of metal or insulation. The stacks are bolted as shown to provide a rigid structure. Stack 20 carries a pair of fixed contact supporting members 23 and 24 of suitable spring material such as spring steel or beryllium copper. Contact carrying members 23 and 24 are bent outwardly away from each other and carry fixed contacts 27 and 28. These contacts may be of any suitable material such as silver, tungsten, or the like.

Cooperating with fixed contacts 27 and 28 are movable contacts 30 and 31 carried on spring arms 32 and 33 diverging from central spring supporting member 34. These arms may be riveted or otherwise fastened to member 34. In the normal rest position of the vibrator, movable contacts 30 and 31 are separated from the cooperating fixed contacts.

Center arm 34 extends upwardly from the stack and its free end 35 is suitably apertured and locked between nuts 36 on threaded end 18 of shaft 17.

Stack 21 carries fixed driving contact 37 mounted on spring arm 38 of the same general shape as arms 24 and 25. Cooperating with fixed contact 37 is movable contact 39 carried on arm 40 branching from spring 41 supported in stack 21. Spring arm 41 has its free end 42 suitably apertured and locked between nuts 43 at threaded end 18 of shaft 17.

As is well known, vibrators may either have the driving contacts in series with the driving coil or in shunt thereto. If the driving contacts are in series, the normal rest position of the vibrator is such as to have the contacts closed. On the other hand, if the driving contacts are in shunt to the driving coil, then the normal rest position of the contacts is open. In such a case, it is customary to dispose the driving coil in series with a primary winding of a transformer, all well known in the art. In this particular instance, the driving contacts are in series with driving coil 13, and these contacts are therefore normally closed.

The spring arms carrying the various contacts are adjusted so that, in the normal rest position, the driving contacts are closed as shown, and the power contacts are open. It is evident that the armature should be on the same side of the center of the coil as the driving contacts. When energized, driving coil 13 will generate a magnetic field tending to move armature 15 toward the left. This will tend to close power contacts 30 and 27 and open driving contacts 37 and 39. As armature 15 moves into bore 14, it reaches a dead center position where the effect of the magnetic field on the armature is a maximum. The driving contacts should be so adjusted as to open at or just prior to dead center.

By adjustment of the contact spacing, mass of the armature and vibrating system, spring tension, it is possible to provide for such an amplitude of movement of armature 15 as to effect a desired and satisfactory closure of power contacts 30 and 27 without undue hammering of these contacts. When driving contacts 37 and 39 are opened, coil 13 becomes deenergized. Thus, the energy stored in the springs of the vibrator tends to return armature 15 toward a normal rest position. In this return movement, armature 15 will overshoot the position indicated in Figure 1, thus closing power contacts 34 and 28. At the same time, driving contacts 39 and 37 will be closed. By proper design of the inductance of the coil and adjustment of driving contacts, it is possible to provide for a closure of the driving contacts so that a retarding force or movement of the armature toward the right of the position shown in Figure 1 will be generated.

It is, thus, clear that the power contacts may be closed without undue hammering. By virtue of the arrangement of the contact supporting arms, a wiping action of the contacts will also result, thus tending to keep them clean. In general, the driving contacts may engage with more force than the power contacts. The driving contacts as a rule do not carry very heavy currents so that but little contact trouble is experienced.

It is evident that driving contacts 37 and 39 may be entirely eliminated, and coil 13 may be

connected across one of the power contacts, contacts 27 and 30 in this particular case.

The amplitude of vibration of armature 15 is preferably small enough for satisfactory vibrator operation. The clearance between the armature and bore of cylinder 14 should be great enough so that no physical contact or sticking can occur.

Referring now to Figures 3 to 5 inclusive, a modified structure is shown wherein the spring mounting for the contacts and armature has been changed. In this particular construction, stacks 50 and 51 carry fixed contacts 52 to 54 inclusive. These contacts may be mounted on straight spring arms with contacts 52 and 53 being power contacts and 54 being a driving contact. Frame members 10' and 11' extend below coil 13 and carry stacks 56 and 57. Stack 56 carries spring 58 at the free end of which are mounted movable power contacts 60 cooperating with fixed contacts 52 and 53 respectively. Spring 58 has portion 61 cut out and small spring 62 left therein. Small spring 62 is fastened to shaft 17' in any suitable fashion.

Stack 57 carries spring arm 64 at the free end of which movable driving contacts 65 is secured. Spring arm 64 is rigidly fastened to shaft 17' as shown, and may have the same cut-out construction as spring arm 58. By controlling the spacers in the various stacks, as well as by bending the various spring arms, adjustment of contact spacing may be made.

Referring now to Figure 6, a push-pull type of construction is shown wherein driving coils 13a and 13b are provided. Shaft 17a carries armatures 15a and 15b spaced as shown. These armatures are disposed axially away from the centers of the corresponding actuating coil. Power contacts 27', 28', 30' and 31' are mounted as shown on spring arms carried by stack 20'. Spring arm 34' carries driving contact 70 cooperating with fixed driving contact 71 carried by spring arm 72 supported in stack 73.

Stack 21' carries spring arm 75 riveted to shaft 17'. Spring arm 75 carries driving contact 76 at the free end thereof, this cooperating with contact 77 carried by stack 78. In the normal position of the device, one of the pairs of driving contacts, here shown as 76 and 77, is normally closed. Upon the energization of the circuit with the connections as shown, coil 13b will be initially energized. Thus, armature 15b will be pulled inwardly to the left. After driving contacts 76 and 77 open, driving contacts 70 and 71 will close. It is understood that both sets of driving contacts will have no over-lapping closure time. When driving contacts 71 and 70 are closed, armature 15a will be pulled back into coil 13a tending to reverse the movement of the vibratory structure. It is clear, therefore, that a push-pull action will result.

It is understood that one movable driving contact may cooperate with a fixed driving contact on each side to alternately engage. Also, one armature, here 15a, may be disposed in a dead center position as the normal rest position. Thus, on closure of contacts 70 and 71, armature 15a would be left of dead center.

The spring structure of the fixed and movable contact arms may be as shown in Patent 2,140,792. In addition, it is possible to utilize the bifilar construction disclosed in Patent 2,012,123 for reducing arcing at the contacts. The vibrator will have the connections shown and, in addition, will be connected to suitable batteries and transformers, all well known in the art.

What is claimed is:

1. In a vibrator, a solenoid including a magnetizing coil, supporting members extending to a supporting structure from said solenoid sides transversely of the solenoid axis, a rod and armature assembly disposed within said solenoid, leaf springs carried by said structure, said leaf springs being normally parallel to each other and normal to the solenoid axis and having cut-outs leaving small spring portions fastened to said rod ends, said leaf springs normally providing an eccentric rest position for said armature and permitting armature movement along said solenoid axis, contacts carried by at least one of said leaf springs, at least one stack carried by said structure, fixed contacts carried by said stack for cooperation with said movable contact and connections between said magnetizing coil and contacts for maintaining continuous vibration upon energization.

2. In a vibrator, a solenoid including a pair of magnetizing coils aligned in side-by-side relation and having a continuous bore, supporting members extending from said solenoid sides transversely of the solenoid axis, a rod and two armatures disposed within said solenoids, leaf springs carried by said supports and being normally parallel to each other and normal to the solenoid axis and supporting said rod at the ends thereof to per-

mit said armatures to move axially within said bore, a driving contact secured to each spring, fixed contacts carried by said supports cooperating with said driving contacts, said armatures being so disposed relative to said solenoids so that only one armature is in a dead center position at one time, one of said pairs of driving contacts being normally closed and connections between said solenoids and driving contacts whereby push-pull vibrator action occurs.
